UNITED STATES PATENT OFFICE.

ALFRED G. F. KUROWSKI, OF BROOKLYN, NEW YORK, ASSIGNOR TO UNDERWOOD

TYPEWRITER COMPANY, OF NEW YORK, N. Y., A CORPORATION OF DELAWARE.

For a Typewriting Machine, for writing or stenciling on cards, and for

partial rotation of the platen in either direction, and for holding the margins of the cards to the platen.

Application filed October 18, 1922. Serial No. 595,235.

To all whom it may concern:

Be it known that I, ALFRED G. F. KUROWSKI, a citizen of the United States, residing in Brooklyn borough, in the county of Kings, city and State of New York, have invented certain new and useful Improvements in Typewriting Machines, of which the following is a specification.

The present invention relates to means, in combination with the rotary platen of a typewriting machine, for facilitating and expeditious the operations involved in the stenciling or printing of cards, such, for instance, as stencil address cards. More particularly, the invention relates to means, of the character mentioned, for use in a front-strike machine, and which provide for introduction of the cards downward, bottom-end first, at the front of the platen, to printing or stenciling position, and for a line-spacing and ejecting movement of the cards with the platen in the usual direction.

A stencil card usually consists of a small piece of stencil paper having a frame or border which consists of cardboard, and this frame is usually of such material that it is not desired to bend the stencil card around the platen. Another difficulty that has been experienced in handling these cards is that they are not easily controlled by the platen and the feeding devices co-operating therewith, so that the cards are liable to skew at the line-feeding operations.

For preventing skewing of the cards in the feed of the same, while avoiding the use of special frames, the platen has heretofore been equipped with bands of fine teeth, for indenting the margins of the cards, and spring-fingers have been provided for holding the margins of the cards to the toothed bands with pressure sufficient to effect such indenting, when, by rotation of the platen, the margins of the cards are introduced between the spring-fingers and the toothed bands.

In the stenciling of cards, such, for instance, as address cards, there are ordinarily but a few lines to be stenciled; and these at definite positions on the card. Partial rotation of the platen in one direction, to bring the card down to initial printing position, and in the other direction for line-spacing and ejecting, is, therefore, ordi-

narily sufficient. By means of stops, this partial rotation of the platen may be so determined that the card is arrested in proper initial printing position without gaging on the part of the operator. It commonly happens, however, that some writing on the top margin of the card is desired, in addition to the stenciling on the body thereof, and in such case a greater rotary movement of the platen, to bring the top margin of the card down to printing position, is required than when stenciling on the body of the card, only, is desired.

For determining the rotary throw of the platen, coacting stops on the end of the platen and opposing side plate of the frame in which it is journaled, have heretofore been provided. The core being ordinarily of wood or of fibrous, relatively soft, material, having the head attached thereto by means such as wood-screws, it has commonly resulted that the constant shocks on the head, as the platen is arrested in its rotary throw, have loosened the screws and head, and have deleteriously affected the accuracy of positioning of the card.

A feature of the invention is the provision of a novel and simple device on the end of the platen-core, for relieving the head-piece, and the screws which secure the head-piece to the core, of shocks such as might otherwise loosen the same in the arrest of the platen in its rotary throw; and for fixedly and durably setting the stop on the platen.

Another feature of the invention is the provision of means whereby the device which determines the rotary throw of the platen in either direction, may, at will, be set for a shorter rotary throw of the platen where no writing on the top margin of the card is desired, or for a longer throw where such writing is desired.

A further feature of the invention is the provision of an improved means, in lieu of the fingers above referred to, for holding the side margins of the cards to the toothed bands on the platen, such improved means to comprise rollers (which are themselves preferably toothed or knurled), and which may be applied with such spring-pressure against the margins of the cards as to cause the latter to be bitten by both the bands and rollers; and therefore assured

of a positive feed, with all possibility of skewing eliminated.

Other features of the invention, in the preferred embodiment thereof, are: the provision of means for releasing the rollers, for insertion and removal of the cards; the provision of a novel form of chute for guiding the cards to position for engagement by the rollers and bands; a novel support common to the rollers and chute; means for adjusting such support for proper positioning of the chute and rollers with respect to the platen; and a novel means for locking the support in adjusted position.

15 Other features and advantages will hereinafter appear.

In the accompanying drawings,

Figure 1 is a top plan view of the carriage of a typewriting machine equipped with the 20 devices of the present invention.

Figure 2 is a front view of the apparatus shown in Figure 1.

Figure 3 is a view, in side elevation, partly cross-sectional, taken on the line 3—3 of 25 Figure 1; the parts, with a stencil-card in place, being shown in position preliminary to reverse movement of the platen to bring the card down to printing position.

Figure 4 is a view, in side elevation, partly cross-sectional, showing the card and card-holding devices, with the card in position for printing upon the upper margin thereof.

Figure 5 is a view, in end elevation, showing the card-holding devices in their relation to the platen; and showing the cap on the end of the platen-head, together with the stops and filler for controlling the line-space feed of the platen.

Figure 6 is a detail perspective view of the 40 filler shown in Figure 5.

The invention is shown as applied to an Underwood typewriting machine. The drawings show the platen-frame found in such a machine. This frame comprises 45 side plates 10, having laterally-offset portions or flanges 11 on their upper edges. A bar 12 connects and holds the plates 10 together at the rear, and, at the front and below the platen, the plates are 50 connected by a rod 13. The rod 13 normally serves as a support for the levers which carry the front and rear pressure rolls (not shown). A rod 14, revolvably supported below the rod 13, serves to throw the pressure 55 rolls. The plates 10 are also connected by a rod 15, which commonly serves as a paper-finger rod. A bracket 16 on the platen-frame carries a roller 17, by means of which the platen frame is supported for its movements in letter-feed and return directions on a rail 18 on a shift-frame 19. The frame 19 is rocked in a well-known manner to lift the platen-frame and platen between lower and upper 60 case positions. Arms 20, pivoted to the

main frame at 21, at their forward ends engage bosses or bushings 22 secured to the side plates 10 of the platen-frame, assist in lifting the platen-frame, and guide the same in its movements between case positions.

70 For making card-stencils a short platen is ordinarily employed. The short platen 23, in the present instance, is merely the curtailment or shortening of the rubber sleeve 24 of the ordinary platen; the wooden core 25, 75 on which the rubber sleeve 24 is fitted, extending to the normal full length of the platen, on both sides of the sleeve 24. The wooden core is provided at both ends with the usual metal heads 26, which set partly 80 into the hollow of the core, and which have flat circular flanges 28 set against the ends of the core and secured to the core by wood screws 29. The heads 26 have bosses 30 by means of which the platen has bearing upon 85 an axle 31, journaled in the side plates 10 of the platen-frame. To each end of the axle 31 may be secured the usual hand wheel or knob 32 for rotating the platen. Also, on the axle or shaft 31, at the left of the platen-frame, is the usual ratchet or line-space wheel 33, on which runs a detent-roll 34, mounted on a spring-pressed arm 35, forming 90 part of the line-spacing mechanism. The latter also includes a handle 36, which 95 returns the carriage frame and platen to the beginning of a new line; this handle usually having an arm 37 to press back a slide 38, and thereby to operate a pawl 39, which engages the ratchet-wheel.

100 According to the present invention, full rotation of the platen is unnecessary; there usually being but two or three lines of stenciling desired on any card, and a writing (which may or may not be desired) on the 105 top margin of the card. Where the writing on the top margin of the card is desired, a greater rotary line-feed movement of the platen is required than where such marginal writing is not wanted. The following provision is made for a shorter rotary movement of the platen, where no top marginal writing is desired, and for a longer rotary movement of the platen when such writing 110 is desired. A cap or cup 40 is snugly set over the right-hand end of the wooden core 25. It is secured by machine screws 41 to the head 26, and by wood screws 42 to the face of the platen beyond the head. The cap 40 has an arcuate slot 43 therein concentric with the axis 31. A pin 44, which holds the boss or bushing 22 to the right-hand end plate 10, is continued beyond the inner face of the plate 10 in line with, and so that, its inner end 45 projects into the slot 43 in the cap 40. The pin 44, therefore, by engagement with the end walls of the slot 43 in the cap, limits and determines the 115 rotary movement of the platen. The slot 43 is of such length as to permit not only of 120

125 130

the several lines of stenciling on the card proper, but also to permit of movement of the platen sufficient to bring the top margin of the stenciling card to the printing line for printing thereon. Where printing on the top margin of the card is not desired, the rotary movement or play of the platen may be shortened, to the amount required for the stenciling on the body of the card, 5 by means of a filler or block 46 (see Figures 5 and 6). This is shown as a flat piece, of arcuate shape, adapted to be laid over the lower or rear portion of the slot 43 to close such portion of the latter. It has a hole 47 at one end to receive a screw 48 for securing it to the outer face of the cap 40. Its other end is recessed at 49 to receive and serve as an abutment for the pin 44, when, by the reverse or card-positioning movement of the 10 platen, the pin 44 is brought thereto. For holding the block or filler 46 against lateral or pivotal movements on its screw 48, it is indented or offset, as at 50, to enter the slot.

Secured by screws 51 to the wooden cylinder 25, at each end of the rubber sleeve, or platen proper, 24, is a metal ring or band 52. The rings or bands 52 have their surfaces serrated to grip the side borders 53 of the stencil-card. The bands 52 are preferably of such width as to grip cards of different widths, and to permit lateral adjustment of the cards on the platen. Effectively to grip the cards, only a slight indentation of the margins thereof, by the bands, 30 when the cards are pressed against the bands by means presently to be described, is necessary. Consequently, the teeth may be quite fine, and need project but slightly beyond the stenciling surface of the platen. The 35 toothed bands are shown as continued entirely around the platen, but need be only of a length commensurate with the length of movement required to feed the card to printing position.

The stenciling is effected against a strip 54 of celluloid, held to the face of the rubber sleeve 24 by a plate 55. The plate 55 extends longitudinally of the platen, from one to the other of the bands or rings 52, 40 and is secured to the platen by screws 56, which pass through the plate and through the rubber sleeve 24, and thread into the wooden core 25. The forward and rear edges of the plate are undercut, as shown at 57, to receive and hold the front and rear edges of the celluloid piece 54. The walls or ledges which determine the undercuts 57 serve as gages for positioning and aligning the celluloid facing-pieces. The celluloid 45 may be slightly bent to be sprung into the undercuts in the plates 55, and, when worn, may be pulled out for replacement.

For holding the margins of the cards with a gripping pressure against the toothed rings or bands 52, there are provided; one for

each band, spring-pressed rollers 58, which, like the bands, have their surfaces serrated or knurled. The rollers 58 are journaled on bushings on headed screws 59 at the forward ends of arms 60. Each of the arms 60 has a boss 61 by means of which it is journaled on a shouldered or headed screw 62, which passes through one leg 63 and threads into the other leg 64 of the U-shaped forward end of a bracket or arm 65. The brackets or arms 65 are made fast, at their rear ends, to a shaft 66, which passes through bosses 67 on the bracket-arms and which crosses from one to the other side piece 10 of the platen-frame. The ends of the shaft 66 are flattened at 68, and screws 69 secure the same to the flanges 11 of the side pieces. Set-screws 70 secure the brackets 65 to the shaft 66; but these set-screws may be loosened to permit of lateral adjustment of the arms 65, as, for instance, when cards of different widths are employed.

The roll-carrying arms 60 have extensions or tails 71 behind their pivot-points 62. The tail 71 of each arm 60 has secured thereto one end of a coil-spring 72, the other end of which coil-spring 72 is connected to an ear 73 on a plate 74 set on the upper rear portion of the corresponding bracket-arm 65 and secured to the bracket-arm by a screw 75. The springs 72, by drawing upward on the tails 71 of the arms 60, maintain an elastic pressure on the rollers 58 on the side margins of any card which may be set between the rollers 58 and the serrated bands 52. To adjust the tension of the springs 72, and consequently of the rollers on the cards, the anchoring plates 74 for the springs 72 are slotted, as at 76, to receive the screws 75, so that the plates may be moved back and forth on the bracket-arms 65. The plates 74 are guided in this movement by ears 77, which are offset over the upper edges of the bracket-arms 65. Upon loosening the screw 75, the corresponding plate may be moved to vary the tension of the spring, and, when the screw is again tightened, the head thereof will hold the anchor-plate in fixed position.

The machine illustrated is a front-strike machine; one of the type-bars 80 being shown in Figure 4 opposite the printing-point. The pressure-rolls 58 are at the front of the platen adjacent the printing-line. The cards or work-pieces are inserted, bottom-end first, at the front of the platen, and are fed down to initial printing-position by a reverse rotary movement of the platen. In the line-spacing and card-ejecting movements of the platen, the cards are fed upward without bending, and are removed at the front of the machine.

A chute is provided for guiding the cards downward to initial printing-position, and for guiding the cards upward in line-spacing.

and ejecting direction. The front wall of this chute is comprised of right and left hand plates 81, preferably of resilient sheet-material, secured, near their upper ends, by 5 screws 82 to the forward lateral offsets of the bracket plates or arms 65. The plates or fingers 81, forming the front of the chute, have openings 83 therein, to accommodate the pressure-rolls 58, and have slits 84 extending upward from the openings 83, to accommodate the arms 60, which carry the pressure-rolls. The fingers 81 are extended below the printing-line, at a rearward incline, and, at their lower ends 85, bear 10 against the shaft 14. The rear wall of the chute is comprised of a pair of sheet-metal plates or fingers 86, having ears 87 offset laterally therefrom, over the front lateral offsets of the bracket-plate 65, between the 15 latter and the fingers 81, and secured to the bracket-arms 65 by the same screws 82 which hold the fingers 81 thereto. Rearward offsets 88 on the fingers 86 provide space between the front and rear walls of the chute 20 for easy movement of the cards therein. At their upper ends, as at 89, the fingers 81 and 86 are turned and bent away from each other, to provide a better mouth for insertion of the cards.

25 With the platen in the position shown in Figure 3, as determined by the pin-and-slot connection 43-45 of the platen with the side plate of the platen-frame, the card 90 is dropped down the chute until, as shown in Figure 3, its bottom margin comes to rest on a ledge 91, formed on the forward edge of the celluloid holding plate 55, with the side margins of the card between the serrated bands 52 and the pressure-rolls 58.

30 At this time, as will presently be described, the pressure of the rolls 58 is relaxed, permitting of free movement of the card between the same and the bands. The ledge 91 serves as a gage to align the card. The 35 card being thus positioned and aligned, the rolls are released to cause the card to be pressed against, and gripped by, the bands. The platen is then rotated until arrested by engagement of the pin 45 with the rear or 40 upper end of the slot 43 in the end cap-piece 40 on the platen. This rotation of the platen, if the filler 46 (see Figure 5) is absent, brings the card to Figure 4 position, with the upper margin thereof at the printing-line opposite the type 80. If, however, the filler 46 is present, rotation of the platen is arrested, with the card in initial position for stenciling at some point below the upper margin thereof. Movement of the card 45 from Figure 4 position upward to stenciling position below the upper margin thereof may be effected by one of the hand-knobs 32 or by the line-space mechanism. The line-space movement of the card for stenciling on the body thereof is effected in the

usual manner by the line-space mechanism. After stenciling has been completed, rotation of the platen is continued in line-space direction until arrested by the pin 45 at the other end of the slot 43. The pressure-rolls 58 may then be released, and the card seized by the upper margin thereof and withdrawn. 70

The pressure-rolls are released and reapplied by the following device. Journaled in the bracket plates or arms 65 is a shaft 92, having fast thereto, near either end, against the outer side faces of each arm 65, a cam-piece 93, having a cam 94 thereon, against which the tail 71 of the corresponding roller-arm 60 is held by its spring 72. When the shaft and cam-pieces 93 thereon are in normal position, the springs 72 hold the pressure-rolls to the bands 52, or to the margins of the cards interposed between the rolls and the bands. When, however, the shaft 92, by means of a handle 95 thereon, is rocked to Figure 3 position, the cams 94 depress the tail-pieces 71, and thereby rock the arms 60 to release the rolls. The normal and roll-releasing positions of the cam-pieces 93 are determined by teeth 96 and 97, respectively, on the cam-pieces, in cooperation with pins 98 projecting from the corresponding bracket-arms 65. Lateral displacement of the shaft 92 is prevented by a collar 99, pinned to the shaft at the left-hand end, and by a similar collar 100 at the right-hand end, which latter, however, is provided with a spline fitting in a groove or slot 102 in the shaft 92, and is held by a set-screw 101. When the set-screw is loosened, the collar 100 may be shifted along the slot, to allow for adjustment of the bracket-arms 65 on the shaft 66, when variation in the setting is desired to accommodate cards of different widths. 95

It is the usual practice to set the handle 95 to the Figure 3 position before inserting a card. After the card has been pressed down between the fingers 81 and 86 to meet the ledge 91 of the platen, the hand of the typist comes in contact with the inclined face of the handle 95 and effects a rearward movement thereof to release the rolls 58 for pressure against the platen. The card may then be run down to the printing field by rotating the knob 32. 100

The bracket-arms 65 are not only supported by the shaft 66, but are also supported by the shaft 15, which passes through openings 104 in the bracket-arms. The openings 104 are of greater diameter than the shaft 15, so as to permit of angular adjustment of the bracket-arms around the shaft 66, for adjustment of the position of the pressure-rolls 58 and of the paper-fingers, forming the chute at the front of the platen, with respect to the platen. For steadyng the bracket-arms 65 on the shaft 15, and for 105 110 115 120 125 130

locking the bracket-arms in desired position, with the shaft 92 horizontal, and with the rolls and chute in proper position, there is, on each bracket-arm 65, a triangular plate 5 106. Each plate 106 has a boss 107 fitted snugly over the shaft 15, and set-screws 108 are provided for locking the plates 106 to the shaft 15. Screws 109 and 110 serve to secure each plate 106 to its corresponding 10 bracket-arm. These screws thread into the bracket-arms 65. The holes in the plates 106 for the screws 109 and 110, however, are larger than the screws, so that, by virtue of the excess size of these holes and of the holes 15 104 in the bracket-arms which receive the shaft 15, a play is allowed between the plates 106 and the bracket-arms 65, when the screws 109 and 110 are loose, thus permitting 20 of the adjustment, referred to, of the bracket-arms. Proper adjustment of the bracket-arms having been obtained, the screws are tightened, and the bracket-arms, with the shaft 92 in the proper longitudinal position, and with the rolls and the chute 25 in proper relation to the platen, are thus firmly held in place.

One of the functions of the cap 40 is to relieve the screws 29 of shocks which would tend to work the same loose in the 30 wooden core. Where the cap is absent and the stops, which determine the rotary throw of the platen, are directly on the head, it has been found that the screws 29 have a 35 tendency to work loose, and, in working loose, disturb the accuracy of feed of the platen. In the present instance, as heretofore noted, the cap, while secured to the head by machine-screws, is also secured to the core by the screws 42, which are directed 40 into the cylindrical face thereof. The snug fitting of the cap on the core and the further anchoring of the cap to the core, by the screws 42, relieve the screws 29 of such shocks as would tend to loosen the head- 45 plate.

Variations may be resorted to within the scope of the invention, and portions of the improvements may be used without others.

Having thus described my invention, I 50 claim:

1. In a front-strike typewriting machine, the combination with a rotary platen, of rollers, arms on which the rollers are mounted, supporting plates to which the roll-bearing arms are pivoted, springs connected to the roll-bearing arms for causing the rollers to press against the platen, and slides adjustable on the supporting plates for anchoring and varying the tension of the 55 springs; said slides having offsets which ride on the edges of their supporting plates, and pin-and-slot connections with said supporting plates, whereby said slides are guided in their movements for adjustment of the tension of the springs.

2. In a front-strike typewriting machine, the combination with a rotary platen, of rollers for holding the margins of a work-piece against the platen, arms on which the rollers are mounted, supporting plates to 70 which the roll-bearing arms are pivoted, and a bar at the rear of the platen on which said supporting plates are bodily swingable, whereby to adjust the position of said rollers relative to the printing line of the platen. 75

3. In a front-strike typewriting machine, the combination with a rotary platen, of a chute at the front of the platen for guiding work-pieces bottom end first to printing position, arms or plates on which the chute is mounted, a support at the rear of the platen on which the arms or plates are pivotally adjustable, a rod passing through a larger opening in the arms or plates, lock plates fast to said rod and set against the chute-supporting arms or plates, and headed screws passing through larger openings in the lock plates and threaded into the chute-supporting plates; whereby, when the screws are loose, the chute-supporting plates, by reason of the size of said rod holes therein, and by reason of the size of the screw holes in the lock plates, may have a limited angular adjustment, and, when the screws are tightened, the chute-supporting plates are 90 locked in adjusted position. 95

4. In a typewriting machine, a rotary platen having an arcuate slot in one end thereof concentric with its axis, a frame in which the platen is journaled, a pin carried by the frame and projecting into the arcuate slot to limit the rotary movement of the platen to the length of the slot, and means for shortening the slot to prescribe a shorter 100 rotary movement of the platen. 105

5. In a typewriting machine, a rotary platen, a frame having side plates in which the platen is journaled, an arcuate slot in one of the opposing faces of said elements concentric with the platen axis, a pin carried by the other of said elements and projecting into the arcuate slot to limit the rotary movement of the platen to the length of the slot, and means for shortening the slot to 110 prescribe a shorter rotary movement to the platen, said slot-shortening means comprising a filler adapted to be set into the slot and removed therefrom at will. 115

6. In a typewriting machine, a rotary platen, a frame having side plates in which the platen is journaled, an arcuate slot in one of the opposing faces of said elements concentric with the platen axis, a pin carried by the other of said elements and projecting into the arcuate slot to limit the rotary movement of the platen to the length of the slot, and means for shortening the slot to prescribe a shorter rotary movement to the platen, said slot-shortening means comprising a filler in the form of a plate 120 125 130

adapted to be set against and secured to the slotted element, and having an offset which projects into the slot when the filler is in place.

- 5 7. In a typewriting machine, a rotary platen, a frame having side plates in which the platen is journaled, an arcuate slot in one of the opposing faces of said elements concentric with the platen axis, a pin carried 10 by the other of said elements and projecting into the arcuate slot to limit the rotary movement of the platen to the length of the slot, and means for shortening the slot to prescribe a shorter rotary movement to 15 the platen, said slot-shortening means comprising a filler in the form of a plate adapted to be set against and secured to the slotted element, and having an arcuate offset of the curvature of the slot, which offset projects 20 into the slot when the filler is in place.

8. In a typewriting machine, a rotary platen, a frame on which the platen is journaled, a member having an arcuate slot therein associated with the end of the platen, 25 a pin carried by the frame engaging said slot for limiting the rotary movement of the platen to the extent required for writing a given number of lines on a work-piece, and means for enlarging such limit to 30 permit of a greater restricted rotary movement of the platen.

9. In a typewriting machine, a rotary platen, a frame on which the platen is journaled, a plate having an arcuate slot therein 35 carried by the end of the platen, a pin projecting into said slot from said frame for limiting the rotary movement of the platen in counter line-space direction to determine the initial printing position of a work-piece 40 fed bottom end first, at the front of the platen, to such printing position, and means for enlarging such limit to permit of a greater rotary movement in said direction, for printing at a higher initial position on 45 the work-piece.

10. In a typewriting machine, a rotary platen comprising a core of wood or other fibrous material, a head-piece secured to the core by screws or pins passing into the end 50 face of the core, a cup set over the head-piece and over the end of the core and having its side wall secured to the core by screws or pins, and its bottom screwed or pinned to the head-piece, a frame in which the platen 55 is journaled, and a pin on the frame projecting into an arcuate slot in the cup concentric with the axis of the platen to limit the rotary movement of the latter.

11. In a typewriting machine, the combination with a revoluble platen, of work-introducing means comprising guides at the front of the platen adjacent each end thereof and arranged to receive the side edges of a work-piece to guide the same downwardly to the printing line, the lower por- 65

tion of the guides flexing the work-piece rearwardly whereby to aid in preventing slippage thereof, and a pair of rolls co-operating with said guides to hold the work-piece, the rolls pressing the upper edge of 70 the work-piece against the platen at a point immediately above the printing line, whereby shadowing of the upper-case type is prevented and the work-piece is in position to receive typing closely adjacent its upper 75 edge.

12. In a typewriting machine, the combination with a revoluble platen, of work-introducing means including a frame disposed above the platen, guides carried by the frame 80 adjacent each end of the platen and arranged to receive the side edges of a work-piece to guide the same downwardly to the printing line, the lower portion of the guides flexing the work-piece rearwardly whereby 85 to aid in preventing slippage thereof, and a pair of rolls pivotally secured to the frame and co-operating with said guides to hold the work-piece, said rolls pressing the upper edge of the work-piece against the platen 90 at a point immediately above the printing line of the platen, whereby shadowing of the upper-case type is prevented and the work-piece is in position to receive typing closely adjacent its upper edge, said frame 95 being movable to adjust the position of said rolls relative to the printing line.

13. In a typewriting machine, the combination with a revoluble platen, of means for introducing a work-piece bottom edge 100 downwardly at the front of said platen comprising two substantially vertically-arranged guides spaced one in front of the other adjacent each end of the platen whereby to provide a pair of oppositely-disposed 105 guiding channels for the side edges of the work-piece, the rear guide being tangential to the platen and having its lower edge terminating thereabove to provide clearance for the platen, and the front guide extending 110 below the printing line to guide the work-piece as it is moved downwardly to typing position at the front of the platen.

14. In a typewriting machine, a revoluble platen, a pivoted frame mounted above the 115 platen, work-piece introducing guides fixed to the frame adjacent the front of the platen, and feed-rolls carried by said frame for pressing against the platen to aid said guides in holding a work-piece during 120 typing thereof, the frame being bodily swingable about its pivot to adjust said frame to different heights whereby to change the position of the feed-rolls relative to the printing line of the platen. 125

15. A typewriting machine having a revoluble platen and releasable feed-rolls to run upon the front thereof to hold a card against the front of the platen, work-introducing means comprising a chute adjacent 130

said feed-rolls and extending up from the front of the platen to guide the card downwardly between the feed-rolls and the platen, the rolls normally pressing against the platen, and a releasable device settable for holding the rolls away from the platen during card-insertion, said device being over the platen and in rear of the chute and adjacent thereto at a height to be engaged and operated by the hand after the card has been pressed down into said chute, said device being so placed that it is operated to release the rolls for pressure against the platen as the bottom edge of the

card is presented to the bite of the rolls of 15 the platen.

16. In a typewriting machine, the combination of a rotatable platen having serrated sections at the ends thereof, releasable serrated rolls supported at the front of said platen and co-operating with said serrated sections to line-feed a stencil-card, a pair of gages mounted upon said platen for gag- 20 ing the stencil-card at the first printing line, and means for automatically limiting the 25 backward movement of said platen.
